[57] ABSTRACT

This invention comprises, in a gun, a sliding breech block mechanism wherein the breech block is connected to at least one pivot carried by a rocker member which incorporates a convex rocker segment in hypocyclic engagement with a coacting concave track formed in, or attached to, the gun: means being provided for inducing, on recoil of the gun, hypocyclic motion of each rocker segment relative to its track whereby the consequent movement of the pivot or pivots operates the breech block.

SLIDING BREECH BLOCK MECHANISM

This invention relates to breech mechanisms and is particularly concerned with a mechanism, actuated by the recoil of a weapon after firing, for operating its sliding breech block.

Use is made of the motion of a circle rolling, internally, around the circumference of a second, coplanar circle. Hereinafter, two circles coacting in this way will be said to be in hypocyclic engagement, the motion of the rolling circle being referred to as hypocyclic motion; these terms being, of course equally applied to cylinders or gears, or segments thereof, which coact in this manner.

This invention comprises, in a gun, a sliding breech block mechanism wherein the breech block is connected to at least one pivot carried by a rocker member which incorporates a convex rocker segment in hypocyclic engagement with a coacting concave track formed in, or attached to, the gun; means being provided for inducing, on recoil of the gun, hypocyclic motion of each rocker segment relative to its track whereby the consequent movement of the pivot or pivots operates the breech block.

By inserting suitable linkages between the breech block and rocker members, a large variety of arrangements of the mechanism is possible. Clearly, however, the use of complicated linkages, particularly those which involve changes in the direction of motion, can lead to considerable losses in efficiency. In order to avoid this, it is preferred to use a special form of the hypocyclic motion device in which the radius of the track is twice that of the rolling member. In this case any point on the circumference of the rolling member will move back and forth along a diameter of the track, its specific diametral path being predetermined by its position on the circumference.

In a preferred form of the invention therefore, substantially, the radius of each rocker segment is half that of its track, their mutually parallel axes being perpendicular to the line of action of the breech block; and each pivot is so located on the pitch circle of a rocker segment that it moves, during hypocyclic motion of the segment, along a diametral path in the coacting track, parallel to the line of action of the breech block. The term "pitch circle" is used herein to define the effective, track engaging surface of a rocker segment, that is to say, the actual pitch circle of a gear or the circumference of a cylinder or the circle of which a segment of either forms a part. Any convenient number of rocker members and tracks may be employed and a track may accommodate one or more rocker members.

The required hypocyclic motion may be conveniently induced by the engagement of one or more rocker members or of attachments thereto, as the gun recoils, with one or more actuating members mounted on a fixed structure such, for example, as a cradle in which the gun is mounted. An actuating member may be a stop located in the path traversed by a rocker member as the gun recoils or, for example, a rack arranged to engage a pinion or a toothed segment which operates the rocker member. In order to allow for variations in recoil of the gun, the arrangement is preferably such that operative engagement between the rocker member and the actuating member is terminated when the breech block is fully opened so that further recoil can take place without further movement of the breech block.

One form of the invention will now be more particularly described, by way of example only, with reference to the accompanying drawings in which:

FIGS. 1 to 3 are horizontal sections through the breech portion of a gun,

FIG. 4 is a section on the line IV—IV of FIG. 1.

FIG. 5 is a side view in the direction V of FIG. 1 but with the stop member and cradle omitted for clarity,

FIG. 6 is a detail of the stop member,

FIG. 7 is a horizontal section through the breech portion of a gun, showing an alternative arrangement,

FIG. 8 is a view in the direction VIII of FIG. 7,

FIG. 9 is a section on the line IX—IX of FIG. 7, and

FIG. 10 is a detail of an alternative stop member.

10 The gun 1 is provided, in normal manner, with a breech block 2 arranged to slide horizontally in a breech recess 3 in a breech ring 4; the breech block 2 having, on its upper and lower faces, projections 5 (FIG. 9) which engage in grooves 6 in the upper and lower faces of the recess 3 to retain the block therein.

15 Formed in the breech ring 4, forward of the breech recess 3 and on that side of the gun 1 to which the breech block moves on opening, is a substantially quadrantal, concave cylindrical track 7 whose axis intersects the path of the breech lock 2 and is perpendicular to both the gun axis and the line of action of the breech block.

20 Pivoted to the breech block 2 is a rocker member 8 of generally semi-cylindrical form having a convex, curved surface comprising rather less than a half cylinder, at each extremity of which, at opposite ends of its bounding diameter, are formed radially projecting lugs 10a, 10b, the remaining, plane surface being parallel to the bounding diameter on the side thereof remote from the curved surface. The curved surface constitutes a rocker segment 9 in rolling contact with the track 7 and its radius is half that of the track. A pivot pin 11 is mounted in the lugs 10a adjacent the breech block 2 the pivot axis passing through

25 the intersection of the circumference of the rocker segment 9 with its bounding diameter, the axis of the pivot 11 being parallel to those of the track 7 and the rocker segment 9. The location of the pivot 11 in the breech block 2 is such that its axis lies in that diametral plane

30 of the track 7 which is perpendicular to the gun axis. With this arrangement, if the rocker segment 9 is constrained to undergo hypocyclic motion relative to the track 7, the pivot 11 and the lugs 10b at the other end of the bounding diameter of the rocker segment 9

35 (hereinafter referred to as the contact lugs) will move respectively along those diameters of the track 7 which are perpendicular to and parallel to the gun axis, the motion of the pivot 11 serving to open or close the breech.

40 55 In order to produce the hypocyclic motion required to open the breech, a stop member 12 is mounted on the gun cradle 13 in the path of movement which will be followed, on recoil of the gun 1, by the contact lugs 10b. This stop member 12 is, on recoil of the gun 1, engaged by the contact lugs 10b which are thus caused to

45 move forward relative to the gun 1, parallel to its axis, the resulting hypocyclic motion of the rocker member 8 being used to open the breech against the action of breech block return springs. A spring loaded catch 14 (shown in FIGS. 7 to 9 only) moves into engagement

50 55 with a notch 14a in the breech block 2, as its opens, to retain it in its open position until the catch 14 is

released by the insertion of a new round 15 of ammunition into the breech, whereupon the breech is closed by the action of the return springs and the rocker segment 9 returns to its initial position by hypocyclic motion in the reverse direction. The new round 15 may be inserted manually or automatically in known manner.

In a preferred form, the stop member 12 consists of a toggle device mounted on the cradle 13 and extending forwardly, toward the gun 1, along the line of movement of the contact lugs 10b. On recoil, the lugs 10b engage the cross member 16 at the forward end of the toggle device whereby the rocker segment 9 is caused to undergo hypocyclic motion in its track 7 to open the breech. In its fully open position the breech block 2 or, as shown, a projection 2a thereon is arranged to engage the toggle hinge 17 to break the toggle lock whereafter the recoil can continue without further movement of the breech block 2. On run out, the toggle device is returned to its locked position by a ferrule 18 actuated by a spring 18a. The forward end of the toggle is constrained to move parallel to the gun axis by the engagement of the pins 36 with grooves 37 in the cradle 13. In the alternative form of toggle shown in FIG. 10 return to the locked position is achieved by the action of a spring 39 wound around the toggle pivot 17a the free ends of which spring engage fore and aft cross members 38a, 38b of the toggle.

An alternative stop member may be in the form of a spring loaded buffer 19 (FIG. 7) 7 whose spring 20 is sufficiently strong to achieve compression of the breech block return springs but which will be compressed to permit further recoil when the breech block 2 engages a solid stop at the fully open position. Various other forms of stop member will occur to those versed in the art.

The breech block 2 is urged toward its closed position by a pair of breech block return springs. In the embodiment shown in FIGS. 7 to 9 these springs 21 are in compression between the block 2 and a yoke 22 which spans that end of the breech recess 3 towards which the breech block 2 moves on opening. These springs 21 are coiled around guide rods 23 fixed to the yoke 22 and in register with corresponding bores 24 in the adjacent face of the breech lock 2, each of which bores 24 serves to house one end of the corresponding spring 21 and to receive the spring 21 and guide rod 23 as the breech is opened. This version also employs a pair of rocker segments instead of the single segment shown in the version of FIGS. 1 to 5.

In the preferred arrangement shown in FIGS. 1 to 6, however closure of the breech is effected by one or more breech block return springs 28 acting indirectly upon the breech block through the rocker member 8 which is thereby caused to execute hypocyclic movement in the reverse direction to close the breech. The rocker member 8 is pivoted, through the contact lugs 10b, to a slide 25 which is movable, parallel to the gun axis, in a guideway 26 carried by the gun 1. The pivot 27, like the breech block pivot 11 is located on the pitch circle of the rocker segment 9. The slide 25 is urged toward its rearward position by the breech block return springs 28 which are helical springs in compression between the forward end of the guideway 6 and the forward end of the slide 25, the said springs 28 being mounted around guide rods 29 fixed to the

guideway 26 and extending into bores 30 in the slide 25. These springs 28 act, on release of the breech retaining catch 14 by insertion of a new round 15 of ammunition, to return the slide 25 to its rearward position thereby inducing hypocyclic motion of the rocker member 8 in the reverse direction to close the breech.

In order to avoid any possibility of premature opening of the breech due to inertia of the moving parts during the initial high acceleration of the gun after firing, 10 at which time the gas pressure in the gun may still be fairly high, a spring latch 31 is pivoted to the rear end of the guideway 26 which latch is biased by spring 32 toward engagement with a coacting notch 33 on the slide 25. This latch 31 prevents movement of the slide 25 until it is disengaged therefrom by the action of cam surfaces 34 upon the cradle 13, with which the upward extensions 35 of the latch 31 come into engagement at a predetermined stage of the gun recoil.

Although it is convenient to arrange the axes of the rocker segment 8 and track 7 perpendicular to the gun axis as well as to the line of action of the breech block 2, this former condition is not essential. The segment can be made to roll in a track whose axis is inclined obliquely, or is even parallel, to the gun axis by wedge action produced by the engagement of suitably inclined faces on the rocker member 8 and stop member 12.

It will be clear that considerable variations of the above described arrangements may be made within the scope of the invention.

I claim:

1. A breech mechanism for a gun equipped with a sliding breech block, which mechanism incorporates a rocker member; a convex rocker segment incorporated in the rocker member; a pivot carried by the rocker member to which pivot the breech block is connected; a concave track movable with the gun and in hypocyclic engagement with the rocker segment and means for inducing, on recoil of the gun, hypocyclic motion of the rocker segment relative to the track whereby the consequent movement of the pivot operates the breech block.

2. A mechanism as claimed in claim 1 wherein the radius of the track is twice that of the rocker segment and the pivot is located on the pitch circle of the rocker segment whereby, during the hypocyclic motion of the segment, the pivot moves rectilinearly along a diameter of the track.

3. A mechanism as claimed in claim 2 wherein the axis of the track intersects the line of action of the breech block and the pivot is so located on the said pitch circle that it will move along that diameter of the track which is parallel to the said line of action.

4. A mechanism as claimed in claim 1 wherein the axes of the track and rocker segment are perpendicular to the gun axis and to the line of action of the breech block.

5. A mechanism as claimed in claim 1 wherein the rocker segment comprises a part cylindrical surface on the rocker member, which surface is in rolling contact with the track which is also part cylindrical.

6. A mechanism as claimed in claim 1 having a fixed structure relative to which the gun recoils, wherein the means for inducing the hypocyclic motion of the rocker segment comprises an actuating member attached to the fixed structure for engaging the rocker member during recoil of the gun, to open the breech.

7. A mechanism as claimed in claim 6 having means for rendering the actuating member inoperative after the breech block has reached the fully open position whereby further recoil can occur without further movement of the breech block.

8. A mechanism as claimed in claim 7 wherein the actuating member comprises a toggle device consisting of two members hinged together and a spring for urging said members to a toggle locked position in which the two members are in line; the rear end of the device being pivoted to the fixed structure, from which the device extends forwardly in the path traversed by the rocker member on recoil of the gun, the forward end of the toggle device being restrained from lateral movement by engagement in guide channels in the fixed member; said toggle device being engaged by the rocker member during recoil of the gun to open the breech and being so positioned that the breech block, in its fully open position, engages the hinge to break the toggle lock whereafter further recoil of the gun, accompanied by folding of the toggle device, can occur without further movement of the breech block.

9. A mechanism as claimed in claim 1 including a fixed structure relative to which the gun recoils and at least one breech block return spring opposing the opening motion of the breech block and wherein the means for inducing the hypocyclic motion of the rocker segment comprises a spring buffer mounted on the fixed structure in the path traversed by the rocker member on recoil of the gun, the strength of the buffer spring being sufficient to overcome the resistance of the breech block return springs to open the breech, said spring however being compressed after the breech block has reached its limit of travel thereby permitting further recoil without further movement of the breech block.

10. A modification of the mechanism as claimed in claim 1 incorporating a plurality of rocker segments.

11. A gun having a breech ring; a breech block slidably mounted in a breech recess in the breech ring; a pair of breech block return springs urging the breech block toward its closed position; a cradle in which the gun is mounted and relative to which it can recoil on firing; and a sliding breech mechanism comprising a quadrantal concave cylindrical track formed in the breech ring forward of the breech recess and on that side of the gun to which the breech block moves on opening, the axis of said track being perpendicular to the gun axis and to the line of action of the breech block and intersecting the latter; a substantially semi-cylindrical rocker member pivoted to the breech block, its curved surface, whose radius is half that of the track, constituting a rocker segment in hypocyclic engagement with the track; a radially extending lug at each end of the bounding diameter of the segment to one of which lugs the breech block is pivoted, the pivot axis intersecting the circumference of the rocker segment

and the line of action of the breech block; and actuating member attached to the cradle in the path traversed by the second lug as the gun recoils to engage said lug to cause the segment to roll forwardly executing hypocyclic motion relative to the track whereby the pivot axis is moved along the diameter of the track to open the breech; a spring latch mounted on the breech ring for engaging the breech block to maintain it open until released by insertion of a new round whereafter the breech block is closed by the action of the return springs.

12. A gun as claimed in claim 11 having yoke fixed across that end of the breech recess to which the breech block moves on opening; a pair of guide rods extending from said yoke into aligned bores in the breech block; the breech block return springs being located around the guide rods and in compression between the yoke and the breech block.

13. A gun as claimed in claim 11 including a guideway located in the breech ring; a slide, slidable parallel to the gun axis, in said guideway, the slide being pivoted to the second lug of the rocker segment; and a pair of guide rods parallel to the gun axis extending rearward from the forward end of the guideway into aligned bores in the slide; the breech block return springs being located around said guide rods and in compression between the guideway and the slide whereby on release of the breech latch the breech block return springs act upon the slide and hence on the rocker segment which consequently executes hypocyclic motion in the reverse direction to close the breech.

14. A gun as claimed in claim 13 including a spring catch mounted on the guideway for engaging the slide to prevent premature opening of the breech due to inertia of the mechanism, on recoil, before the gas pressure in the gun has sufficiently reduced; and a cam surface on the cradle arranged to engage and release said catch after the pressure has sufficiently reduced but before engagement of the rocker segment with the actuating member.

15. A gun as claimed in claim 11 wherein the actuating member is a toggle device comprising a pair of members hinged together and a spring urging the toggle to a locked position in which the two members are in line; said toggle device being pivoted at one end to the cradle and extending forwardly therefrom in the path traversed by the second lug of the rocker segment on recoil of the gun, the forward end of the toggle device being restrained from lateral movement by engagement with guide channels formed in the cradle; the toggle device being positioned so as to be engaged by the breech block at its fully open position to break the toggle lock whereafter further recoil can occur, accompanied by folding of the toggle, without further movement of the breech block.
